UNITED STATES PATENT OFFICE.

AUGUST REININGER, OF SAN FRANCISCO, CALIFORNIA.

DESIGN FOR A FOB.

41,693.

Specification for Design.

Patented Aug. 22, 1911.

Application filed June 10, 1911. Serial No. 632,525. Term of patent 3½ years.

To all whom it may concern:

Be it known that I, AUGUST REININGER, a citizen of the United States, residing at San Francisco, in the county of San Francisco and State of California, have invented a new, original, and ornamental Design for Fobs, of which the following is a specification, reference being had to the accompanying drawing, forming part thereof.

The figure is a plan view of a fob, showing my new design.

I claim:

The ornamental design for a fob, as shown.

AUGUST REININGER.

Witnesses:

F. M. WRIGHT,
D. B. RICHARDS.
